US00D738391S

(12) **United States Design Patent**
Everingham et al.

(10) **Patent No.:** US D738,391 S
(45) **Date of Patent:** ** Sep. 8, 2015

(54) **PORTION OF A DISPLAY SCREEN WITH A GRAPHICAL USER INTERFACE**

(75) Inventors: **James R. Everingham**, Santa Cruz, CA (US); **Amy Lee**, San Mateo, CA (US)

(73) Assignee: **Yahoo! Inc.**, Sunnyvale, CA (US)

(**) Term: **14 Years**

(21) Appl. No.: **29/403,826**

(22) Filed: **Oct. 11, 2011**

(57) **CLAIM**

The ornamental design for a portion of a display screen with a graphical user interface, as shown and described.

DESCRIPTION

FIG. 1 is a front view of a portion of a display screen with a graphical user interface showing the new design; and, FIG. 2 is a front view of a second embodiment thereof. The dashed lines showing lines and images form no part of the claimed design. Said dashed lines and dashed image are presented only for environmental purposes.
